Lackenbach Siegel, LLP(57) **CLAIM**

The ornamental design for an earring back, as shown and described.

DESCRIPTION

FIG. 1 is a front top perspective view of an earring back showing my new design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof; and,

FIG. 7 is a bottom plan view thereof.

The item is a back for a post-mounted earring.

The broken lines in the drawing depict the boundary of the claim. It is understood that the claim extends to the boundary but that the boundary forms no part of the claim.
